UNITED STATES PATENT OFFICE.

MADGE GRIFFIN, OF SAN FRANCISCO, CALIFORNIA.

DESIGN FOR AN ELECTRIC-LIGHT WALL BRACKET.

Application filed November 6, 1923. Serial No. 7,700. Term of patent 7 years.

To all whom it may concern:

Be it known that I, MADGE GRIFFIN, a citizen of the United States, residing at the city and county of San Francisco, State of California, have invented a new, original, and ornamental Design for an Electric-Light Wall Bracket, of which the following is a specification, reference being had to the accompanying drawing, forming part thereof.

The figure is a perspective view of an electric light wall bracket showing my new design.

I claim:

The ornamental design for an electric light wall bracket, as shown.

MADGE GRIFFIN.
